STRAP STRETCHING AND SEALING DEVICE

William C. Childress, Oak Park, Ill., assignor to
Acme Steel Company, Chicago, Ill., a corpora-
tion of Illinois

Application August 22, 1932, Serial No. 629,798

16 Claims. (Cl. 81—9.1)

This invention relates to strap stretching and sealing devices and its purpose is to provide a combination tool which may be employed to stretch a metal strap around a box or bale, for example, and then unite the overlapping ends of the strap by means of a seal which is applied thereto by the tool and deformed in order to form an interlocking joint. The device of the present invention is in many respects similar to that described in my co-pending application Serial No. 592,050, filed February 10, 1932, but differs chiefly in the fact that the present improvement is adapted to hold and apply to the overlapping strap ends a separate metal seal, whereas the device of said application is intended primarily to unite the overlapping ends of a strap by deforming portions of the strap alone to provide an interlocking joint. The principal object of the present invention is to provide an improved device adapted to stretch a strap taut around a box or package, or a group of boxes or packages, and then unite the ends of the strap by means of a seal which is held in the tool during the process of applying it to the strap. Another object of the invention is to provide an improved strap sealing device embodying improved means for holding and accurately positioning a metal seal for application to overlapping strap ends by relative movement of certain parts of the tool. Another object of the invention is to provide an improved strap sealing device comprising means for permitting a channel-shaped seal to be snapped into interlocking engagement therewith in readiness for application to the ends of the strap to be united thereby. A further object of the invention is to provide a combination stretching and sealing device having means for stretching the strap taut, then cutting off the strap from the source of supply and finally uniting the ends of the strap by means of a seal which is automatically held in the device while being applied to the overlapping strap ends. Other objects relate to various features of construction and arrangement which will appear more fully hereinafter.

The nature of the invention will be understood from the following specification taken with the accompanying drawings, in which one embodiment is illustrated. In the drawings,

Fig. 1 shows a side elevation of a box and of the improved stretching and sealing device of the present invention in position to apply a reinforcing strap or binder about the box;

Fig. 2 shows a perspective view of a form of

seal adapted for use with the present invention;

Fig. 3 shows a top plan view of the seal joint which is formed by the use of the present invention;

Fig. 4 shows a side elevation of the joint illustrated in Fig. 3;

Fig. 5 shows a sectional view taken on the line 5—5 of Fig. 3;

Fig. 6 shows a sectional view taken on the line 6—6 of Fig. 3;

Fig. 7 shows a top plan view of the lower portion of the device of the present invention, a portion thereof being illustrated in horizontal section taken on the line 7—7 of Fig. 8;

Fig. 8 shows a front elevation of the improved strap stretching and sealing device illustrated in Figs. 1 and 7;

Fig. 9 shows a vertical section taken on the line 9—9 of Fig. 7;

Fig. 10 shows a vertical section taken on the line 10—10 of Fig. 8;

Fig. 11 shows a vertical section taken on the lines 11—11 of Figs. 7 and 8;

Fig. 12 shows a vertical section taken on the line 12—12 of Fig. 16;

Fig. 13 shows a vertical section taken on the irregular line 13—13 of Fig. 7, illustrating the relative positions of the parts when the movable seal carrying head is in its normal upper position;

Fig. 14 is a perspective view of the movable cutting blade and die;

Fig. 15 is a perspective view of the stationary cutting die;

Fig. 16 is a sectional view like that of Fig. 13, showing the relative positions of the parts after the movable head of the device has been lowered to effect the cutting off of the strap from the source of supply and to cause the seal to embrace the overlapping ends of the strap;

Fig. 17 is a vertical section taken on the line 17—17 of Fig. 7, showing the relative positions of the parts when the jaws of the seal carrying head have been moved inwardly toward each other to bend the seal about the strap ends and effect the shearing of the edges of the strap and seal;

Fig. 18 is an enlarged sectional view taken on the line 18—18 of Fig. 22, showing the relative positions of the jaws when the head is in its upper position with a seal inserted between the jaws;

Fig. 19 shows a sectional view taken on the line 19—19 of Fig. 18;

Fig. 20 is a sectional view similar to that of

Fig. 18, showing the relative positions of the parts after the jaws have been closed upon each other to bend the side walls of the seal about the overlapping strap ends and to effect the shearing of the edges of the strap and seal to form an interlocking joint;

Fig. 21 shows, on a reduced scale, a bottom plan view of the jaws and side plates of the movable head before placing a seal therein; and

Fig. 22 is a bottom plan view of the seal and head, similar to that of Fig. 21, showing a seal in place between the jaws.

As illustrated in Fig. 1, the improved strap stretching and sealing device 25, embodying the features of the present invention, is illustrated in position on top of a box 26 which has applied thereto a pair of steel straps 27 which surround the box and which are united at their ends by means of the device 25 shown in operative position with respect to one of these straps. The ends of each strap 27 are adapted to be engaged by gripping devices embodied in the tool 25 which is then operated to draw the strap taut around the box. When this stretching operation has been completed, the sealing device is operated to place over the overlapping strap ends a channel-shaped metal seal which has previously been inserted in the movable head of the tool and the downward movement of this movable head is adapted to place the seal in position over the strap ends and then to bend the walls of the seal about the strap and shear the edges of the strap and seal to form an interlocking joint of the type described and claimed in the United States patent of Ralph H. Norton No. 1,260,016, dated March 19, 1918. The improved sealing device of the present invention is adapted particularly to operate upon an improved form of seal 30, shown in Fig. 2, which is described and claimed in the co-pending application of Chester M. MacChesney Serial No. 629,918, filed August 22, 1932, now issued as Patent Number 1,988,742, dated January 22, 1935. This seal is in the form of a channel-shaped member having a back wall 30^a and side walls 30^b which diverge therefrom to their outer edges. This flared arrangement of the side walls of the seal permits it to be readily applied to the overlapping ends of the strap and facilitates the holding of the seal in the sealing device 25 during the operation of applying it to the overlapping strap ends. This seal is formed of metal which is hard and stiff but which has a slight resiliency and sufficient ductility to cause it to retain a permanent set after the walls 30^b have been bent around the ends of the strap. The edges of the side walls 30^b are punched outwardly at points midway between their ends to form outwardly extending projections 30^c which serve to position the seal within the tool as hereinafter described.

After the ends 27^a and 27^b of the strap have been overlapped and while they are held taut by the stretching device, the end 27^b of the strap is cut off from the source of supply and the sealing blank 30 is operated upon by the device 25 to bend the walls 30^b inwardly beneath the strap ends into position where they lie substantially parallel to the top or back wall 30^a located on the upper side of the strap. The cutting dies carried by the movable jaws of the device 25 then operate upon the lateral edges of the strap and seal to shear them along transverse lines 31. At least one pair of cuts 31 is preferably formed along each edge of the seal and the metal between the cuts of each pair is deflected downwardly by the cutting dies to form angularly dis-

posed tongues or projections 32, the edges of which cross the edges of the body portions of the strap and seal along the lines 31, thus forming an interlocking joint, as shown particularly in Figs. 3, 4, 5, and 6.

The sealing device 25 comprises a base plate 33 which is adapted to rest upon the surface of a box or package about which a strap 27 is to be drawn taut and sealed. This plate 33 preferably has the irregular contour shown in Fig. 7 and the forward portion thereof is provided with a pair of relatively movable gripping devices which are adapted to grip the opposite end portions of the strap and to hold them while the strap is being drawn taut. For this purpose, the forward portion of the base plate 33 is provided with an upwardly extending integral block or boss 34 having an overhanging flange 34^a adapted to conform to and contact with the curved upper edge of a gripping dog 35 which is pivotally mounted upon a pin 36 engaging the back wall of this boss, as shown particularly in Fig. 10. This gripping dog 35 is provided on its under side with a serrated gripping surface 35^a which is adapted to coact with the upper side of the end portion 27^a of the strap 27 when this strap is seated upon the gripping plate or flange 37 projecting from the forward edge of the base plate 33. This gripping plate or flange has its outer edges beveled as shown at 37^a to facilitate the insertion of the strap in position beneath the gripping dog 35 which is similarly provided with a tapered projecting portion 35^b adapted to cooperate with the beveled surface 37^a to form a tapered passage to receive the strap. The serrated surface 35^a of the gripping dog 35 is offset, toward the right as viewed in Fig. 8, with respect to the vertical plane of the pivot pin 36 so that when the end 27^a of the strap is inserted beneath it, a pull on the strap toward the left, as viewed in Fig. 8, will tend automatically to increase the grip of the dog 35 upon the strap. When a pull is exerted upon the strap in the opposite direction, the dog 35 tends to release its grip so that the strap may be readily removed from its position over the plate 37. The gripping dog 35 is provided between its gripping surface and the pivot pin 36 with an inwardly extending slot 35^c adapted to receive the body portion of the strap 27 after the strap has been passed around the box or package. This supply portion of the strap is adapted to be held in this slot 35^c by frictional engagement with a ball 38 which is pressed downwardly by a coil spring 39 engaging a recess in the gripping dog 35 and an aligning passage in the overhanging portion of the boss 34. A threaded plug 40 adjustably engages the upper end of the passage in the boss 34 to coact with the upper end of this spring and this plug may be adjusted to vary the compression of the spring which, in addition to maintaining the ball 38 in contact with the supply portion of the strap 27, also forces the dog 35 downwardly into engagement with the end portion 27^a of the strap which is seated upon the plate or flange 37.

After the strap 27 has been inserted beneath the dog 35 and passed around the box or package, the other end portion 27^b thereof is placed in position to be gripped by a movable gripping device comprising a block 44 which is slidably mounted on the front portion of the base plate 33 at the end thereof opposite the block 34, being secured by cap screws 45 to the end of a bar 46 which is slidably mounted on the base plate for movement parallel to the front edge thereof 75

and to the direction in which the strap is passed around the package. As shown particularly in Figs. 7, 8, and 11, the block 44 comprises an overhanging portion 44^a which is curved to conform to the curvature of the contacting gripping dog 47 which is pivotally mounted upon a pin 48 engaging the rear wall of the block. The gripping dog 47 is provided on its under side with a serrated gripping surface 47^a which is adapted to 10 coat with the upper side of the end portion 27^b of the strap when the strap is seated upon the gripping plate or flange 49 which projects forwardly from the lower part of the block 44. The gripping dog 47 is inclined so that the gripping surface 47^a is offset toward the left, as viewed in Fig. 8, from a vertical plane passing through the axis of the pin 48 so that a pull upon the strap 27 toward the right, as viewed in Fig. 8, tends to increase the grip of the dog 47 upon 15 the strap, while a pull upon the strap in the opposite direction serves to effect the automatic release of the strap from the grip of the dog. This gripping dog 47 is moved into engagement with the strap by a coil spring 50 which engages 20 a passage 51 formed in the overhanging portion of the block 44 with one end thereof engaging the inclined upper surface of the gripping dog and with the other end engaging a plug 52 which 25 threadedly engages the passage 51 to permit adjustment of the compression of the spring. The plate 44^b of the block 44 which is secured upon the upper side of the bar 46 by the studs 45 has a projection 44^c which extends rearwardly beyond the bar 46, as shown in Fig. 7. This projecting lug is adapted to be engaged by a stud screw 53 which threadedly engages a boss 54 formed on the base plate 33. This screw 53 may be adjusted in its position within this boss and held in place by a lock nut 55 so that it determines the initial position of the block 44 at the commencement of the strap stretching operation. This permits a variation in the amplitude of the stretching movement of the block 44 and the gripping dogs carried thereby.

45 The bar 46 slides in a groove 56 which is formed in the upper side of the base plate 33, as shown particularly in Figs. 13 and 16, and it is held against upward movement by the bars 57 and 58 which are secured to the upper side of the base 50 plate to bridge the groove 56 in spaced relation to each other. The extremity of the bar 46, opposite the block 44, is reversely bent, as shown in Fig. 9, to overlie the end of a lever 60 which is pivotally secured to the end of the bar by a pin 61. The lever 60 extends rearwardly over the base plate 33 and has an intermediate point thereof pivotally connected by a pin 62 to a link 63, the forward end of which is pivotally secured to the stationary block 58 by means of a pin 64 which passes through the upper and lower flanges 58^a and 58^b, respectively, of this block, as illustrated in Figs. 7 and 9. The lever 60 is adapted to be oscillated about the pin 62 to cause it to assume the position shown by dotted lines at 60^a in Fig. 7, thereby causing movement of the block 44 toward the block 34 for the purpose of drawing the strap 27 taut around the box or package. The lever 60 is reenforced on its upper side by a bar 60^b which has the forward portion thereof 55 bent upwardly to overlie the rear end of the link 63, as shown in Fig. 13, and the rear end of the lever 60 is reversely bent to form a part 60^c which extends parallel to the body portion thereof and which is adapted to receive beneath it the rear flattened end 65^a of a link 65. This link 65 is

5 pivotally connected to the lever 60 by a pin 66 which passes vertically through the body portion of the lever, through the reenforcing bar 60^b and through the reversely bent portion 60^c. These parts are embraced and held against upward movement by a yoke 67 which is secured to the base plate 33 by screws 68 extending upwardly from the bottom thereof, as shown in Fig. 13. The forward end of the link 65 has a flange 65^b, lying in a vertical plane, which engages the slot 10 69^a formed in a crank arm 69 which is constructed integrally with the hub 70^a of an operating lever 70 adapted to be manually manipulated to effect the stretching of the strap. The flange 65^b of the link 65 is pivotally connected to the crank 15 arm 69 by a pin 71 and the hub 70^a of the operating lever is secured by a transverse pin 72 upon a shaft 73 which is journaled in bushings 74 mounted in apertures formed in upwardly extending arms or posts 75 secured to or formed integrally with the base plate 33. A washer 76 of leather or other friction material is secured to the side of one of the posts 75 to bear against the hub 70^a of the lever or handle 70 and a coil 20 spring 77 is mounted on the shaft 73 to bear against a collar 78 fixed on the shaft and against the bushing 74 in the post 75 adjacent the hub 70^a and thus hold the shaft 73 in its bearings and maintain the hub 70^a in frictional contact with the leather washer. This construction is adapted 25 to hold the lever 70 in any desired adjusted position, thus maintaining a corresponding fixed spaced relation of the blocks 34 and 44 after the strap has been drawn taut by the operation of the handle 70. An important advantage of this construction is that the operation of the lever 70 produces a rapid relative movement of the blocks 34 and 44 during the early part of the stretching operation when the strap is comparatively slack, while the rapidity of motion decreases and the force exerted upon the strap increases as the final stages of the stretching operation are approached. This permits the tool to be used in stretching a strap in a single operation 30 as compared with the use of several tools or several operations, which has been the practice 35 heretofore.

40 The sealing of the overlapping ends of the strap by the application thereto of a seal 30 is effected by a movable head 80 comprising a pair of side plates 81 which are pivotally mounted on a shaft 82 fixed in the lower parts of the posts 75, as shown particularly in Fig. 17. The plates 81 are notched on their upper sides as shown at 81^a to receive the shaft 73 when they are in their uppermost positions and they are adapted to receive between them a pair of jaw members 83 which are pivotally mounted upon pins 84 secured in the side plates 81. Each jaw member 83 is preferably formed as an integral member and is provided on its inner side with a curved surface 83^a concentric with its pivotal axis and adapted to move in proximity to the corresponding surface on the other jaw member, as shown in Figs. 17, 18, and 20. Between these curved surfaces, there is mounted a seal supporting member or saddle 85 which is substantially triangular in cross-section, having curved surfaces 85^a, which are adapted to coat with the curved surfaces 83^a of the jaw members. This saddle 85 is provided at each end with an integral projecting trunnion 85^b and these trunnions engage apertures in the side plates 81 to support the saddle in position between the jaw members which are thus capable 50 of relative movement without disturbing the po- 55

sition of the saddle. The lower portions of the jaw members 83 are provided with inwardly projecting hooks or jaws 83^b having notches 83^c therein to receive the lower portions of the side walls 30^b of the seal 30 when this seal is placed in position between them, as shown in Fig. 18. The lower walls 83^d of these notches engage the extreme edges 30^d of the seal and thus hold the seal in place in position to straddle the overlapping ends of the strap 27 when the head 80 is lowered from its normal upper position, shown in Fig. 13, in which the seal 30 is placed therein. The members 83 are under-cut beneath the jaws 83^b as shown at 83^e. The jaw members are further provided with slots 83^f which extend inwardly from the lower edges thereof through the jaws 83^b and through the curved surfaces 85^a. These slots 83^f are adapted to be engaged by cutting dies 87 which have cutting edges 87^a projecting into the under-cut recesses 83^e beneath the jaws 83^b, and these flattened portions engage the side walls or openings 83^g which are formed in the jaw members 83^h which are engaged by the enlarged cylindrical portions 87^c of the cutting dies. Each of the bores 83^h is enlarged at its outer end to receive a pair of threaded plugs 88 which may be locked in adjusted position to hold the adjacent cutting die 87 in a position wherein it will project to the desired extent inwardly beneath the adjacent jaw 83^b. The edges of the slots 83^f in the jaw members are adapted to form complementary cutting dies which cooperate with the dies 87 to effect the shearing of the edges of the strap and seal as the jaws 83^b approach the final limitations of their inward movement toward each other. The effect of the initial movement of the jaws toward each other is to bend the side walls 30^b of the seal inwardly beneath the overlapping strap ends and to move the back wall of the seal against the saddle 85. As the relative movement of the jaw members continues, the cutting dies 87 engage the edges of the seal and effect a shearing action as shown in Fig. 20, while at the same time deflecting portions of the strap and seal to form the projecting tongues 32.

The jaw members 83 have arms 83ⁱ which extend upwardly from the pivot pins 84 and which are pivotally connected at their upper ends by pins 89 with links 90 which engage slots 83^j formed in the upper ends of these arms. The links 90 are pivotally connected by pins 91 with opposite sides of the hub portion 92^a of an operating lever 92 which is pivotally mounted on a pin 93 carried by the side plates 81. The turning of the lever 92 about the pin 93 is adapted to spread the links 90 and the arms 83ⁱ of the jaw members so that the jaws 83^b of these members are moved inwardly toward each other to effect the operations upon the seal 30 which have previously been described. When the head 80 is in its uppermost position, as shown in Fig. 13, the elongated hub 92^a of the operating lever is positioned endwise between the arms 83ⁱ of the jaw members and a projection 92^b on the hub engages a spacer bar 94 which extends between the side plates 81, thus limiting further movement of the lever 92, toward the left as viewed in Fig. 13. The jaw member 83 which is nearest the pivotal axis 82 of the head 80 is connected to the pin 82 by a pair of links 96 and 97. The link 96 is pivotally connected to the jaw member by a pin 98 and is pivotally connected at the other end to the other link 97 by means of a pin 99. The lower

end of the other link 97 is pivoted on the pin 82 and is spaced midway between the side plates 81 by sleeves 100. The link 96 has one corner rounded as shown at 96^a to permit its rotation in an upward direction in the slot 97^a of the link 97 which receives the end of the link 96, as shown particularly in Fig. 7, but the downward pivotal movement of the link 96 is prevented by the engagement of its rectangular upper corner with the end of this slot. When the two links 96 and 97 are in alignment with each other, as shown in Fig. 13, the axis of the pin 99 is located below or to the right of a plane containing the axes of the pins 98 and 82 so that the two links thus act as a toggle connection between the jaw members 83 and the pivotal axis of the head 80, so that relative movement of the jaw members is prevented while the links occupy this position. This permits the head 80 to be moved downwardly by the operating lever 92 without relative movement of the jaw members and with this lever in the position shown in Fig. 13, until the seal 30 held between the jaws has been passed over the overlapping strap ends. At this point, the link 97 engages a stop member 101 which is threaded to engage an aperture in the base plate 33 so that it may be adjusted vertically and secured in the desired position by a lock nut 102. When the link 97 contacts with this stop member 101, the toggle connection formed by the links 96 and 97 is broken so that the lever 92 is then permitted to move in a forward direction about its pivot 93, thereby separating the upper arms 83ⁱ of the jaws 83 and causing the lower parts thereof to close upon the strap and seal to effect the bending of the arms of the seal about the overlapping strap ends and then the shearing of the edges of the strap and seal.

In order to permit the seal to be inserted between the jaws with the head 80 in the upper position shown in Fig. 13, one of the links 96 is provided with an elongated slot 90^a for engagement by the connecting pin 89 so that a limited pivotal movement of one jaw is permitted and this allows the seal 30 to be pushed upwardly between the jaws 83^b until the lower edges of the side walls 30^b thereof snap into engagement with the recesses 83^c behind the jaws. The flaring walls of the seal facilitate this insertion of the seal because they exert a wedging action upon the opposite jaw members which is adapted to separate them sufficiently to permit the seal to be snapped into position. When the seal is inserted, the projections 30^e on the side walls thereof are located in alignment with the slots 83^f in the jaw members and these projections engage these slots when the seal reaches the position shown in Fig. 18 so that the seal is thus positioned properly between the jaws with the middle portions of the seal in alignment with the cutting dies 87. When the seal 30 is thus inserted, it is held resiliently in position between the jaws by the action of a pin 103 which is mounted in a tubular passage 104 formed in one jaw member with its extremity engaging the inner face of the other jaw member, as shown in Fig. 13. The enlarged head of this pin is slidably mounted in the enlarged portion 104^a of the passage through the jaw member and is engaged by a coil spring 105 mounted in this passage and held in position therein by a threaded plug 106 located in the end of the passage. This spring 105 may thus be adjusted to exert the desired pressure for separating the upper ends of the jaw members and causing the lower portions thereof to grip the side walls of the seal 30.

The flange 37 of the base plate 33 extends transversely of the base plate for a considerable distance and underlies the forward portion of the block 58 which is secured upon the base plate, as previously described. The base plate 33 has another forwardly projecting flange 107 which extends outwardly parallel to the flange 37, leaving an inwardly projecting notch or opening 108, between these flanges, which is located in registry with the path of movement of the jaws 83 as they are lowered, so that the jaws may be closed about the seal and strap in this opening while the strap is supported on the adjacent flanges 37 and 107, the latter of which is beveled on its upper side at its forward end to permit the convenient insertion of the strap. At the commencement of the operation of applying a strap 27 around a box or package, the free end 27^a of the strap is first inserted between the gripping dog 35 and the flange 37 of the base plate with the extremity of the strap projecting across the opening 108 and resting upon the flange 107, as shown in Fig. 8. The strap is then passed around the box or package and the portion 27^b thereof which is connected to the source of supply is then passed beneath the gripping dog 47 so that it is held against the flange 49 carried by the movable block 44. After being passed beneath the gripping dog 47, the supply portion 27^b of the strap is placed in position over the extremity of the free end 27^a of the strap on the flange 107, as shown in Fig. 8, and beneath the forward end of the block 57 which is beveled on its under side to permit the strap to be received in the slot which is thus formed between this block and the flange 107. The strap is then inclined upwardly toward the left, as illustrated in Fig. 8, and passed over a stationary cutting die 110, from which point the supply portion of the strap is carried over the flange 37 of the base plate and caused to occupy the slot 35^c in the gripping dog 35. The cutting die 110 has the form shown particularly in Fig. 15, being provided with two oppositely extending plates 110^a each of which has a cutting edge 110^b. At its middle point, the die has an upwardly extending lug 110^c which is apertured for engagement by a bolt 111 by which it is secured to a flange 58^a formed on the block 58. When thus secured in place by the bolt 111, the lower edge of the die 110 rests upon the upper surface of the base plate. The under portions of the forward edges of the blades 110^a of the die 110 are inclined upwardly as shown at 110^d, in Figs. 13 and 16, to facilitate the insertion beneath this cutting blade of the free end portion 27^a of the strap. The bolt 111 may be removed and the die 110 reversed in its position in order to bring its other cutting edge into operation.

After the strap has been placed in the position described in the last paragraph, the lever 70 is moved rearwardly, toward the left as viewed in Fig. 13, thus causing the lever 60 to assume the position illustrated by dotted lines in Fig. 7, with the result that the bar 46 and block 44 are moved toward the left, as viewed in Figs. 7 and 8. This causes the supply end 27^b of the strap to be carried with the block 44 by the gripping dog 47, with the result that the strap is drawn taut around the box or package. The degree of tightening which is effected by a single operation of the hand lever 70 may be varied by adjusting the initial position of the block 44 through manipulation of the adjustable stop member 53, illustrated in Fig. 7. After a seal 30 is inserted 75 between the jaws 83, in the manner described

above, the strap is drawn taut by operating the lever 70, and the operator then moves the handle 92 forwardly, toward the right as viewed in Fig. 13, thereby causing the head 80 to lower without any relative movement of the jaws 83 and without any pivotal movement of the lever 92 with respect to the head 80, until the link 97 engages the stop member 101 and breaks the toggle connection previously described. During this preliminary movement of the head 80, the stretched 10 strap is cut off from the source of supply by the operation of a shearing lever 114 which carries a detachable cutting blade 115, having the form shown particularly in Figs. 13 and 14.

This shearing lever 114 is in the form of a bell 15 crank lever pivoted at an intermediate point on the bolt 111, previously described. The upwardly extending arm 114^a of this lever is pivotally connected through a pin 116 with a link 117 which is in turn pivotally attached by a pin 118 to one 20 of the side plates 81 of the head 80. A coil spring 119 is connected to the pin 116 at one end and has its other end attached by a screw 120 to the lower portion of one of the posts 75 carried by the base plate so that this spring tends 25 normally to rock the shearing lever 114 in a direction to elevate the arm 114^b thereof upon which the blade 115 is secured in a recess by the screw 121. The action of this spring 119 tends also to elevate the head 80 about the pin 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

spring 119, as illustrated in Fig. 13. The operator then reverses the motion of the stretching lever 70 with the result that the block 44 is moved toward the right, as viewed in Fig. 7, 5 thereby releasing the sealed strap from the grip of the dog 47. The tool may then be moved toward the left, as viewed in Fig. 7, and away from the strap to release the strap from the dog 35, so that the strap is then permitted to snap 10 downwardly into close contact with the top surface of the box or package. The tool of the present invention thus provides a simple and efficient device by which the strap may first be drawn taut around the box or package, then cut 15 off from the source of supply, and finally sealed by the bending and shearing of a channel-shaped seal which is held in position by the tool itself during the stretching, cutting and sealing operation.

20 Although one form of the invention has been shown and described by way of illustration, it will be understood that it may be constructed in various other forms coming within the scope of the appended claims.

25 I claim:

1. The combination in a sealing device, of a base plate, a movable head mounted on said base plate, a pair of relatively movable jaws mounted on said head, means for causing said jaws to hold an open seal inserted between them, means for effecting relative movement of said jaws to bend said seal about overlapping strap ends, and means including a toggle connection between one 30 of said jaws and said base plate for preventing relative movement of said jaws until a predetermined movement of said head has taken place.

2. The combination in a sealing device, of a base plate, a movable head mounted on said base plate, a pair of relatively movable jaws mounted 40 on said head, means for causing said jaws to hold an open seal inserted between them, means for effecting relative movement of said jaws to bend said seal about overlapping strap ends, a pair of links forming a toggle connection between 45 one of said jaws and said base plate for normally preventing relative movement of said jaws, and an adjustable stop member carried by said base plate for coacting with one of said links and breaking said toggle connection after a predetermined movement of said head.

50 3. The combination in a strap sealing device, of a movable head, a pair of jaws pivotally mounted on said head and adapted to receive an open seal between them, an operating lever pivotally mounted on said head, operating connections between said lever and said jaws including means for permitting a limited relative movement of said jaws without movement of said lever, and resilient means for causing said jaws to exert pressure on the sides of an open seal 55 placed between them.

4. The combination in a strap sealing device, of a movable head, a pair of jaws pivotally mounted on said head and adapted to receive an open seal between them, an operating lever pivotally mounted on said head, operating connections between said lever and said jaws including means for permitting a limited relative movement of said jaws without movement of said lever, resilient means for causing said jaws to exert pressure on the sides of an open seal placed 60 between them, means for preventing relative movement of said jaws by said lever during the initial movement of said head from its normal position, and means for releasing said last named

means and thereby permitting actuation of said jaws by said lever to bend said seal about overlapping strap ends.

5 5. The combination in a sealing device for overlapping strap ends, of a pair of relatively movable jaws adapted to receive a channel-shaped seal between them, said jaws having inwardly directed parts adapted to overlap the side walls of said seal, and resilient means for causing said jaws to exert pressure on said side 10 walls.

6. The combination in a sealing device, of a pair of pivotally mounted jaw members having inwardly directed jaws adapted to receive a channel-shaped seal between them, said jaws 15 having parts adapted to overlap the edges of the side walls of said seal, said jaw members having arms extending on the opposite sides of their pivotal axes from said seal-engaging jaws, and means for exerting a resilient pressure on said 20 arms to cause said jaws to hold said seal in position to embrace overlapping strap ends.

7. The combination in a sealing device, of a pair of pivotally mounted jaw members having inwardly directed jaws adapted to receive a channel-shaped seal between them, said jaws having parts adapted to overlap the edges of the side walls of said seal, said jaw members having arms extending on the opposite sides of their pivotal axes from said seal-engaging jaws, means for 30 exerting a resilient pressure on said arms to cause said jaws to hold said seal in position to embrace overlapping strap ends, and actuating means engaging said arms of said jaw members for effecting relative movement thereof to bend the side 35 walls of said seal about said strap ends.

8. The combination in a sealing device, of a pair of relatively movable members adapted to receive between them a channel-shaped seal, said members having oppositely disposed recesses 40 adapted to be engaged by projections on said seal.

9. The combination in a sealing device, of a pair of relatively movable members adapted to receive between them a channel-shaped seal, said 45 members having oppositely disposed recesses adapted to be engaged by projections on said seal, and shearing dies mounted in said recesses for engaging said seal after a predetermined relative movement of said members.

50 10. The combination in a sealing device, of a movable head, a pair of jaws pivotally mounted on said head to receive a channel-shaped seal between them, said jaws having notches to receive projections carried by said seal, means for causing said jaws to hold said seal between them, means for moving said head to cause said seal to embrace overlapping strap ends, cutting dies carried by said jaws, and means for effecting relative movement of said jaws after said movement of said head for shearing the edges of said strap.

11. The combination in a sealing device for connecting overlapping strap ends, of a pair of relatively movable jaws having oppositely disposed parts adapted to receive between them a channel-shaped seal having outwardly flared side walls, said jaws having oppositely disposed notches adapted to receive the edges of said side walls, and means for causing said jaws to hold said seal in position therein.

12. The combination in a sealing device for connecting overlapping strap ends, of a pair of relatively movable jaws having oppositely disposed parts adapted to receive between them a

channel-shaped seal having outwardly flared side walls, said jaws having oppositely disposed notches adapted to receive the edges of said side walls, and means for causing said jaws to hold said seal in position therein, said jaws having notches therein to engage projections formed on said side walls of the seal.

13. The combination in a strap stretching device, of a base plate, a pair of gripping devices carried by said base plate for gripping the end portions of a strap looped around a package, means for effecting relative movement of said gripping devices to draw said strap taut, a reversible shearing blade detachably secured on said base plate, and a movable blade adapted to cooperate with said reversible blade to sever the strap from the source of supply after it has been drawn taut.

14. The combination in a strap stretching device, of a base plate, a pair of gripping devices carried by said base plate for gripping the end portions of a strap looped around a package, means for effecting relative movement of said gripping devices to draw said strap taut, a reversible shearing blade detachably secured on said base plate, a movable blade adapted to cooperate with said reversible blade to sever the strap from the source of supply after it has been drawn taut, means carried by said base plate for applying a seal to the ends of said strap to form an interlocking joint, and means for actuating said movable blade when said last named means is operated.

15. The combination in a strap stretching and sealing device, of a base plate, strap stretching means carried by said base plate for drawing a strap taut around a package with its ends overlapping above and parallel to an edge of said plate, means for operating said strap stretching

means, a head comprising a pair of side plates pivoted on and adjacent to said base plate and adapted to swing toward said overlapping strap ends, a pair of jaws pivotally mounted between said side plates and having oppositely disposed hook portions adapted to engage and hold the walls of a channel-shaped seal positioned between them, an operating lever connected to said jaws and pivotally mounted between said side plates, said lever being adapted to swing about an axis parallel to the pivotal axis of said side plates, and dies carried by said jaws for deforming said seal and said overlapping strap ends upon relative movement of said jaws after said head has been lowered to position said seal over said overlapping strap ends.

16. The combination in a strap stretching and sealing device, of a base plate, strap stretching means carried by said base plate for drawing a strap taut around a package with its ends overlapping above the edge of said plate, means including a lever movable transversely to said strap for operating said strap stretching means, a head pivotally mounted on said plate, a pair of jaws carried by said head and adapted to receive and hold an open channel-shaped seal between them, an operating lever carried by said head and connected to effect relative movement of said jaws, means operatively connected with said jaws for preventing relative movement thereof when pressure is initially applied to said lever whereby said initial pressure effects bodily movement of said head toward the strap ends, and means adapted to actuate said last named means to permit relative movement of said jaws upon further movement of said lever in the same direction for effecting the deformation of the strap ends and said seal to form an interlocking joint.

WILLIAM C. CHILDRESS.
